(Cl. D44—22)

To all whom it may concern:

Be it known that I, Frank Richard Hale, a citizen of the United States of America and resident of the city of Paterson, Passaic County, and State of New Jersey, have invented a new, original, and ornamental Design for a Combined Salt and Pepper Shaker or Similar Article, of which the following is a specification, reference being had to the accompanying drawing, forming part thereof.

Figure 1 is a front elevational view of a combined salt and pepper shaker or similar article showing the new design;

Figure 2 is a side elevational view of the same;
Figure 3 is a top plan view of the same;

Figure 4 is a side elevational view of the lower or base portion of the shaker, with the cover removed, and

Figure 5 is a top plan view of the lower or base portion.

I claim:

The ornamental design for a combined salt and pepper shaker or similar article, substantially as shown.

FRANK R. HALE.
